DESIGN FOR A COOKY

George W. Burry, Hillside, N. J., assignor to Burry Biscuit Corporation, Linden, N. J.

Application September 11, 1936, Serial No. 64,822

Term of patent 3½ years

To all whom it may concern:

Be it known that I, George W. Burry, a subject of the King of Great Britain, residing at Hillside, in the county of Union and State of New Jersey, have invented a new, original, and ornamental Design for Cookies, of which the following is a specification, reference being had to the accompanying drawing, forming part thereof, wherein,—

Fig. 2 is a view in elevation of a cooky, showing my new design.

I claim:

The ornamental design for a cooky, as shown.

GEO. W. BURRY.
